UNITED STATES PATENT OFFICE.

WILLIAM WYAND, OF ABSECON, NEW JERSEY.

GRATE SECTION.

Application filed April 5, 1926. Serial No. 99,821.

This invention relates to the grates used in steam boilers for burning low grade coal or culm which has much dirt and dust in it; and it consists of a grate section or fuel plate constructed as hereinafter fully described and claimed and operating to burn such low grade fuel to very great advantage.

In the drawings, Figure 1 is a plan view 10 of a grate section constructed according to this invention. Fig. 2 is an end view of the same. Fig. 3 is a cross-section, taken on the line 3—3 in Fig. 1. Fig. 4 is a side view of the grate section. Fig. 5 is a cross-section 15 similar to Fig. 3 but shows a simple form or modification of the ribs which extend over the air channels.

The grate is formed of a multiplicity of 20 similar grate sections supported in a frame of any approved construction. The grate sections are usually arranged end to end in as many rows as will make the grate of the required width, but each grate section may be supported in a separate pocket in the 25 frame if desired.

Each grate section is integrally formed, and is provided with two longitudinal supporting bars 6 arranged parallel to each other. Inner crossbars 7 are formed between 30 the longitudinal bars 6, and are spaced apart to form oblong air channels 8. The tops of the crossbars are flush with the tops of the widest part of the longitudinal bars, and the crossbars are substantially one-half the 35 depth of the longitudinal bars. Outer crossbars 9 project from the opposite sides of the longitudinal bars 6, and are preferably extensions of the inner crossbars 7, but they do not necessarily have to be in line with 40 them. Oblong air channels 11 are formed between the outer crossbars 9.

The bars 6, 7 and 9 are all tapered in cross-section, so that the air channels all converge upwardly. The crossbars 9 are 45 preferably of the same width and depth as the crossbars 7, and their tops are also flush with the longitudinal bars 6. Lugs 10 are formed on one side of the crossbars 7 and 9 at one end of the grate section, and have 50 vertical air channels 12 between them. The lugs 10 assist in supporting the grate section in the frame.

Ribs 14 and 15 are formed longitudinally 55 of the grate section, and are arranged parallel to each other and at substantially equal distances apart. Two of these ribs 14 are

arranged over the wide upper parts of the longitudinal bars 6. One rib 15 is arranged crosswise over the inner crossbars 7 midway of their length, and a similar rib 15 is arranged substantially midway of the length of each of the outer crossbars 9. These ribs 14 and 15 are narrower than the wide upper parts of the longitudinal bars 6, and they 60 form a series of longitudinal channels 16 which are relatively shallow, each channel being about twice as wide as deep. The ends 17 of the ribs are preferably rounded off. The ribs 15 project above the crossbars 9 and across the air channels 11 between them, and 65 their bottoms 18 are preferably arranged a little below the level of the tops of the crossbars, and are rounded or inclined so that the air may pass upwardly freely from the air channels below them. The ribs 15 are 70 preferably cylindrical in form between the crossbars, but the exact form is not material. They are preferably made of a size that will permit the metal to flow freely in the mold, so that satisfactory castings can be made in 75 large quantities.

In the form of the grate section shown in Fig. 5, the bottoms 18' of the ribs 15' are arranged level with the tops of the crossbars. This is a satisfactory arrangement 80 for burning the fuel, but is less satisfactory to manufacture in quantities, and the ribs are liable to burn away more quickly, than in the form shown in Fig. 3. In each form the ribs prevent clinkers from being formed 85 in the air channels, and as the major portions of the air channels are unobstructed the air can pass upwardly very freely to all parts of the fuel. The open-ended air channels 11 enable the imperforate surface of 90 the grate to be reduced materially. The openings at the tops of the air channels are made of substantially equal area by spacing the ribs and bars as shown.

A suitable poker or other tool is slid along 100 the longitudinal channels 16 between the ribs as often as necessary to stir up the fuel and break up clinkers which have formed. The ribs also support the rake used for removing the clinkers, and prevent it from 105 catching in the oblong air passages and jerking the grate sections out of position in the frame. The air is divided up into small streams by the air channels, so that a complete combustion of fuel is effected. The 110 deep longitudinal bars 6 afford the necessary strength to prevent the grate section from

2
breaking, and more or less of them, and more or less than five ribs can be provided for supporting the fuel, but five ribs are preferred for ordinary boiler grates.

5. What I claim is:

1. An integrally formed grate section for burning culm, comprising longitudinal supporting bars, inner crossbars extending between the longitudinal bars and forming 10 oblong air channels, outer crossbars projecting from the outer sides of the longitudinal bars and forming oblong open-ended air channels, and longitudinal upwardly projecting ribs which extend crosswise over 15 the tops of the said air channels and over the surfaces of the crossbars between them, said ribs being of much less depth than the crossbars and leaving the air channels between the crossbars substantially unobstructed.
2. A grate section as set forth in claim 1, the said longitudinal bars and crossbars being tapered in cross-section and widest at their upper parts.
3. A grate section as set forth in claim 1, and having the bottoms of the said ribs rounded or inclined to permit the air to pass freely upward on each side of them.
4. A grate section as set forth in claim 1, and having the said ribs formed substantially cylindrical over the said air channels.
5. A grate section as set forth in claim 1, and having also longitudinal ribs arranged at the tops of the longitudinal supporting

bars intermediate of the adjacent ends of 35 the air channels.

6. A grate section as set forth in claim 1, and having also longitudinal ribs arranged at the tops of the longitudinal supporting bars intermediate of the adjacent ends of 40 the air channels, all of the said ribs being arranged at substantially equal distances apart, and the openings at the tops of the air channels being all of substantially equal area.

7. An integrally formed grate section comprising longitudinal bars, crossbars extending between the longitudinal bars and forming a series of oblong air channels, said crossbars having extensions which project at the outer sides of the longitudinal bars and form two series of open-ended air channels, and longitudinal ribs arranged above the tops of the said crossbars and their extensions and extending across them and the air passages between them, said ribs being of much less depth than the crossbars and leaving the said air channels substantially unobstructed.

8. A grate section as set forth in claim 7, 60 and having also lugs on one side of the crossbar and its extensions at one end of the grate section, air channels being formed between the said lugs.

In testimony whereof I have affixed my 65 signature.

WILLIAM WYAND.
